NECKTIE RACK

Jacob R. Kissinger, San Diego, Calif.

Application October 6, 1939, Serial No. 298,249

2 Claims. (Cl. 211—13)

My invention relates to necktie racks, and its objects are to provide a convenient support for a number of neckties from which any one may be readily selected and removed, to afford individual and separate mountings for holding neckties in accessible position, for packing and compressing such neckties and for preserving the same in unwrinkled and flattened condition, and guard the neckties from dirt and exposure, to construct a convenient depressed wall receptacle or closet for the reception of neckties, and in general to simplify and render more effective the operation of the several parts.

I am aware that heretofore attempts have been made to construct racks for the display of neckties, and to afford opportunity for the selection of individual ties therefrom; but so far as I am aware I am the first person in the art to devise a series of individually spring actuated rollers arranged in a tier for the support and packing of neckties, and the ready installation and removal of single neckties therefrom without disturbing the remaining neckties. Other objects and novel features will appear as illustrated in the drawing and as hereinafter described and claimed.

Attention is hereby directed to the drawing, in which similar numerals of designation refer to similar parts throughout the several views, and in which—

Figure 1 is a front view of an opened shallow box containing a tier of my improved necktie rollers, showing them provided in part with neckties duly installed, and showing a necktie in the act of being rolled into packed position;

Fig. 2 is an enlarged view of one of the rollers and frame shown in Fig. 1;

Fig. 3 is an end elevation of the view shown in Fig. 2 and illustrating the locking thumbscrew and adjacent parts;

Fig. 4 is a view of a modified necktie roller designed to be operated by a hand crank;

Fig. 5 is an end view of two modified rollers and frames constructed to be attached to a ceiling, and novel locking means therefor;

Fig. 6 is a side elevation of one of the rollers and connections shown in Fig. 5, and

Fig. 7 is a plan view on the inner end of the roller and adjacent parts shown in Fig. 2.

Referring to the drawing—within the shallow cabinet or box 7 composed of wood, metal or other suitable material, I firmly affix at one side thereof the vertically disposed standard 8. Pivotedly secured to said standard are the frames 9, preferably constructed of an integral metallic

strip having a horizontal member 10, and end members 11 and 12, the latter of which is provided with the arms 13 and 14 whose ends are rotatably mounted to swing outwardly upon the standard 8. As shown, the frames 9 are arranged one above another to form a tier or rack, the outwardly swinging ends of which, pivotally secured to the standard 8, are separated by the washers 15 in order to obtain greater freedom 10 of movement.

Upon the upwardly extending parts of each frame is rotatably mounted a necktie roller 16 in a manner similar to that of the roller of an ordinary shade curtain and similarly provided 15 with a coil spring and connection to effect releasable rotation thereof. In place of the ratchet usually employed, however, I prefer to use the thumb screw 17, the shank of which is threaded to engage with and extend through a threaded 20 opening in end member 11, and to contact with the outer end of the roller 16, and to lock the same against rotation. Located at the outer swinging end of each of said rollers and extending longitudinally over the surface thereof is the 25 resilient finger 18, constructed releasably to receive and firmly hold against said surface the end or a fold of a necktie 19.

The box 7, while preferably rectangular in form as shown, and provided with a hinged cover 30 20, may be of any desired shape or configuration suitable for the purpose. In the preferred form shown in the drawing, I purposely make the same shallow, in order to allow the box to fit into an opening (in the wall of a room) shaped for its 35 reception, and to permit the said cover of the box when closed to become flush with said wall so as to merge into the same and to be decorated in conformity therewith.

In the modification of my invention shown in 40 Fig. 4, I rotatably mount my improved roller directly upon the wall and rotate the same manually by means of the crank 21. In the modifications shown in Figs. 5 and 6, I construct the frames 22 of a different form from frame 9 as 45 shown in Figs. 1, 2 and 3, and slidably suspend the same from brackets 23 secured to the ceiling of a room or closet, a chain 24, attached to the outer end of said frame and provided with a peg 25 engaging with a socket 26 in the end of the 50 roller, serving to lock the same against rotation in a manner similar to thumb screw 17. If desired, this chain locking means could be substituted in Figs. 1 and 2 for the thumb screw 17 there shown, or the crank 21 could be used in lieu thereof. Also, if desired, the horizontal 55

member 10 may be set closer to the roller 16 so as to narrow the space therebetween and permit the free end of the necktie to become wedged or secured in position.

In order properly to pack the box 7 with a full complement of neckties, I swing the roller frames 9 one at a time into the position indicated by the fifth frame (counting from the top) shown in Fig. 1, that is, a position substantially at right angles with the bottom of the box and extending outwardly into the room or closet where my rack has been installed. One of said frames being in such position, and the spring of the roller therein being adjusted to its greatest tension, I secure the end or a fold of the necktie under the finger 18, and releasably permit the roller to revolve and to wind such necktie closely therein and to form smooth helical folds or wrappings covering the roller and extending nearly to the inner end thereof, and thereupon to lock the roller from further rotation by means of the thumb screw 17. In so winding the necktie upon the roller, care should be taken that the same may be pressed down perfectly flat, so that when this winding is completed, the tie will be free from wrinkles and its shape carefully preserved. This operation is repeated until each of the rollers 16 is loaded, and turned back into the box, and until the box is fully packed with neckties and the cover closed. Thereafter, as a necktie is needed, its frame may be swung outwardly, the thumb screw unlocked, and the necktie pulled from its roller.

As will be observed, the periphery of the roller 16 is located sufficiently close to the horizontal member 10 of the frame 9, as to permit said member 10 to act as a guard in preventing the necktie from being unwound to any substantial extent once it is rolled and packed in position.

In the modification shown in Fig. 4, the necktie is manually wound upon the roller by means of the crank 21, and is released therefrom by pulling the necktie until it is unwound and separation is effected from the roller. In Figs. 5 and 6 the operation is similar to that of the rollers shown in Figs. 1, 2 and 3.

My invention may be embodied in other specific forms without departing from the spirit or essential characteristics thereof. The present embodiment of my invention as hereinbefore set forth is therefore to be considered in all respects as illustrative and not restrictive, the scope of my invention being indicated by the appended claims, and all changes which come within the meaning and range of equivalency of the claims are therefore intended to be embraced therein.

What I claim and desire to secure by Letters Patent is:

- 20 1. In a necktie rack, the combination of an upright standard, an integral metallic frame having a horizontal member and two upright members, one of which has two arms whose ends are rotatably mounted upon said standard, a horizontal type of roller mounted upon said upright members, and means connected with said frame for locking said roller against rotation.
- 25 2. In a necktie rack, the combination of an upright standard, an integral metallic frame having a horizontal member and two vertically extending members, one of which has two horizontally extending arms whose ends are rotatably mounted upon said standard, a horizontal type of roller rotatably mounted upon said vertically extending members, and means connected with said frame for locking said roller against rotation.

JACOB R. KISSINGER.
